(57) **CLAIM**

The ornamental design for a timing chain cover for a motorcycle engine, as shown and described.

DESCRIPTION

FIG. 1 is a perspective view of a timing chain cover for a motorcycle engine embodying our new design, the dotted lines representations form no part of the claimed design; FIG. 2 is a top plan view;

FIG. 3 is a right side view thereof;

FIG. 4 is a front elevational view thereof;

FIG. 5 is a rear elevational view thereof;

FIG. 6 is a left side view thereof; and,

FIG. 7 is a bottom plan view thereof.
